UNITED STATES PATENT OFFICE.

OTTO LINGOHR, OF SOLINGEN, GERMANY.

DESIGN FOR A TOY FIGURE.

40,342.

Specification for Design.

Patented Nov. 9, 1909.

Application filed July 30, 1908. Serial No. 446,205. Term of patent 3½ years.

To all whom it may concern:

Be it known that I, OTTO LINGOHR, a subject of the German Emperor, and resident of Solingen, Germany, have invented a new, original, and ornamental Design for Toy Figures, reference being had to the figure of the accompanying drawing, showing the design of the toy figure in an elevation.

I claim:—

OTTO LINGOHR. [L. s.]
